UNITED STATES PATENT OFFICE.

ALBERT KOCH ANDRIANO, OF SAN FRANCISCO, CALIFORNIA, ASSIGNOR TO DIRECT-LINE GENERAL TELEPHONE COMPANY, OF SAN FRANCISCO, CALIFORNIA, A CORPORATION.

DESK-TELEPHONE AND SWITCHING MECHANISM.

No. 853,855.

Specification of Letters Patent.

Patented May 14, 1907.

Application filed July 22, 1905. Serial No. 270,758.

To all whom it may concern:

Be it known that I, ALBERT KOCH ANDRIANO, a citizen of the United States, residing in the city and county of San Francisco and State of California, have invented new and useful Improvements in Desk - Telephones and Switching Mechanism, of which the following is a specification.

This invention relates to a novel telephone outfit for a subscriber's use, of such form and construction that it can be placed in one of the pigeon-holes or compartments of an office-desk where it will be out of the way, and yet will be always at hand for use. In an outfit of this character, consisting of a transmitter and a receiver, and a line-switching means for selecting and making connection with the lines of other subscribers, the stand, case or box that incloses the switching mechanism also furnishes a support for the transmitter and receiver.

One object of the invention is to produce a combined switching device and a support for the transmitter and receiver of such form that the case or box containing the same can be set in the pigeon-hole of a desk and the instruments conveniently operated in that position.

The invention has for its object, also, to so connect or combine the transmitter and the switching-device that in operating the switch to set up a circuit with another station the user is compelled to move the transmitter and thereby agitate the particles of carbon as often as the switch is moved.

A further object of the invention is to so combine or arrange the parts of the telephone that the receiver will cover the transmitter, and the two instruments will mutually protect their diaphragms while the receiver remains on its hook.

To these ends and objects, chiefly, the invention consists in certain novel construction and combination of box or case, transmitter and line-switching mechanism, as hereinafter fully described and afterward pointed out in the claims at the end of this specification.

The accompanying drawings referred to in the following description illustrate a telephone outfit adapted to sit in a "pigeon-hole" compartment of an office-desk, and embodying the several features of my invention.

Figure 1 represents the complete outfit or apparatus in side-elevation, with the receiver in place on the hook; Fig. 2 is a front-elevation, showing a portion of the outer case broken away to expose the dial-plate of the switch. Fig. 3 is a side-elevation similar to Fig. 1, but with the casing removed and the receiver off the hook. Fig. 4 is a transverse section taken through Fig. 3 on the line 4-4, showing the stationary-contacts and the movable-contact of the line-switch. Fig. 5 is a transverse sectional-view at 5-5 showing the circle of stationary contacts that are situated on the right side of the section-line. Fig. 6 is a sectional-view taken through 6-6 showing the circuit-closing contacts situated on the back panel of the case that are controlled by the telephone-hook. Fig. 7 is a rear-view of Fig. 5. Fig. 8 is a longitudinal vertical section of a portion of the apparatus, the first panel and other parts being omitted.

The switching-mechanism, by the construction and arrangement of its parts, is capable of being contained in a case or box of small dimensions and of a size that will readily slip into one of the pigeon-holes, or compartments, usually provided in the front of an office-desk.

Referring to the drawings in the following description, A indicates the box or case; T, the transmitter; R, the receiver and H, the telephone-hook. The front-plate a, the base-block a¹ of insulating fiber, and the upright blocks or panels a², a³, a⁴ of the same insulating material may be termed the frame of the device. This frame is inclosed by a cover composed of the top B and the sides C-C, which is made removable to afford access to the parts.

On the front and intermediate panels a² a³ are the stationary contacts 2-3, 4-5 of the switch through which the conductors of the local transmitting and receiving circuit are connected into the line-wires to complete the circuit for calling up and talking with other stations. In the space between the two panels last mentioned the rotatable switch-piece b, composed of or provided with two contact-arms b¹-b²-b³-b⁴ is fixed on opposite sides of the insulating center-piece 6.

The novel feature of this invention in connection with the switching mechanism, is in

combining the transmitter and the switch so that the transmitter forms or furnishes a hand-piece for rotating and setting the movable-member from one switch-point to another; and in carrying out this part of the invention the transmitter is formed with a cylindrical extension, or hub 7, on the back, and sockets in which it is fitted to turn, are provided in the center of the circle of switch-contacts on both panels. The switch-piece *b* is fixed on that part of the hub 7 which lies between the two panels *a*²—*a*³, and the portion of the hub that passes through the panels is of smaller diameter than the portion lying in front of the first panel *a*². A collar 10 is fixed on that end prevents the hub from being drawn out of place. The hub 7 serves also as a conductor to make continuous metallic connection between the transmitter—*T*—and the internal wiring of the instrument, for which purpose it is composed of the outer metallic sleeve carrying the collar 10, and a central core 12, which is separated from the sleeve by insulation 13. The end of the core 12 extending beyond the sleeve is uncovered as seen at 12 Figs. 7 and 8, and on this exposed portion of the core a conducting strip 15 fixed on the back of the panel *a*³ makes continuous contact. A similar strip 16 rests in like manner on the collar 10, and the two strips serve to connect the wires of which they are the terminals on the panel *a*³ separately and directly with the inner and the outer conducting portions of the hub 7 under all changes in the position of the transmitter produced by rotating to operate the switch.

The circle of stationary-contacts 2 on the front face of the panel *a*³ are the individual terminals or switch-points of the incoming line-wires from the other stations in the system, and the contact-arms *b*¹—*b*² of the switch-piece *b*, by connecting any selected one of these switch-points 2 with the centrally placed contact-ring 3 operate to close the circuit through the selected line-wire and the conductor of which the ring 3 constitutes the terminal in the switch.

Stationary contact-rings 4—5 on the opposing face of the panel *a*² in front are situated in the ringing-circuit, and as they are electrically connected or separated by the second set of contacts *b*³—*b*⁴ on the switch-piece they close or open the circuit through the ringing-battery and the bell at the opposite station on the selected line according to the position given the switch-piece in the adjustment of the first-mentioned contacts *b*³—*b*⁴, whether set to close a line-circuit, or else moved off the line-contacts to select and set up a different circuit.

A switching-mechanism of this character for selecting and controlling circuits for talking by the operation of the ringing-circuit has been made the subject of a separate appli-

cation by me in an application dated March 15 1905, Serial No. 250,154, and I do not consider it necessary to describe more specifically the construction and operation of the two sets of contacts for completing separate ringing and talking circuits, by the movable switch-piece, because the same form no part of the present invention, that may, or may not, be provided with the set of contacts 4—5 in connection with the principal switch-contacts 2—3 according to the particular style or construction of switch required for the circuits or system in which this mechanism is to be used.

The position of the movable-member of the line-switch is indicated to the user in the well-known manner by a dial-plate 20 fixed on the hub 7 of the transmitter behind the front-plate *a* of the case, in which a sight-aperture 21 exposes to view one switch-number at a time. The back-panel *a*⁴ furnishes a support for those circuit-closing springs that are controlled in the usual way by the telephone-hook; one set 22—23 being connected together to close the circuit for ringing up the station while the receiver is on the hook, but the other sets 24—25, 26—27 being disconnected at such time, and only connected when the receiver is taken down for use. The arm *H* of the hook is pivotally attached at 28, on the front panel *a*² of the frame, from which point 28 one arm or member *h*¹ extending rearwardly is connected to a circuit-closing lever 30 by a link or connection 31, and the other member *h*² in front of the pivot extends beyond the frame at the front to furnish a support for the receiver *R*. The arm *h*² is of such length that the hook-bearing end *h*² when depressed by the weight of the receiver will support the receiver in front of and hold it against the mouth-piece *t* of the transmitter *T*, as seen in Fig. 1, in which position the mouth-piece will be covered, and will in its turn cover the end of the receiver.

The style of telephone-receiver used in this outfit, and illustrated in the drawing, commonly known as a watch-case receiver, is by its shape well adapted for the purpose of constituting a cover or protector for the transmitter, and also by its compact form and small size taking but little room when hanging on the hook.

The manner of wiring the instrument to connect the switching mechanism with the line-wires will be readily understood by those who are familiar with setting up and operating telephone-circuits of the kind in which a switching-device is provided at every station for making connection and ringing-up other stations without the interposition of a "central" office. The line-wires are individually connected to the posts 32 on the back of the panel *a*³, so that the stationary-contacts 2 on the front-face of the panel form

terminals of all the line-wires. The intermediate stops 2* in the circle are blank stops arranged to separate the line-contacts 2. The contact-stops in the circle on the back of the 5 first panel a^2 are metallic parts of the ring 4 through which the arm b^3 b^4 of the switch-piece by its contact therewith and with the ring 5 completes a circuit through the ringing-battery to operate a circuit-controlling 10 device interposed in the talking-circuit—as before referred to. The arm b^1 b^2 of the switch-piece closes the circuit between the stationary contact-ring 3 of the line-switch and that particular one of the line-terminals 15 on which the movable arm b^1 may be placed by the rotation of the switch-piece b to select the line. A simple rotation of the mouth-piece t^1 to the right or left will bring the switch on the desired line, the position being 20 indicated at the sight-aperture in the front of the case. Each operation of the switch thus produces rearrangement of the carbon particles in the transmitter; and special attention or treatment of the transmitter from 25 time to time to agitate the carbon is altogether unnecessary. As often as the telephone is used the transmitter must be rotated to make the switch.

Having thus described my invention, what 30 I claim is:—

1. A telephone outfit comprising a case containing the terminals of a plurality of lines, a movable transmitter having a mouth piece at the front of the case, a line-selecting switch connected with and moved by the transmitter, a receiver adapted to cover the opening of the said mouth piece, and means for holding the receiver in position against the mouth piece when not in use, substantially as set forth.

2. In a line-selecting telephone outfit a case, a transmitter therein movable to effect the line-selecting and having its mouth-piece on the front of the case, a receiver adapted to 45 cover the mouth-piece, and a pivoted telephone-hook arranged to hold the receiver in position against the mouth-piece of the transmitter, and also to control the switches of the local telephone outfit.

3. In a telephone outfit, a case, a line-switching-mechanism having a movable switch-piece, a series of stationary contacts and a transmitter movable in the case and connected with the movable switch-piece 55 whereby the adjustment of the switch-piece is effected by moving the transmitter.

4. In a line-selecting local telephone outfit, the combination of a case, line contacts within the case, switching mechanism therein, a 60 movable switch-piece co-operating with the said line contacts, and a rotatable transmitter adapted to form the setting means for the switch-piece.

5. In a telephone outfit, the combination

of a case, a series of stationary contacts for 65 the ringing circuit, a series of stationary contacts for the talking circuit, a movable switch-piece for each of said circuits, and a transmitter movably mounted in the case and arranged to set the said switch-pieces when 70 moved, substantially as set forth.

6. In a telephone outfit, the combination of a case, a series of stationary contacts for the ringing circuit, a series of stationary contacts for the talking circuit, a transmitter 75 rotatably mounted in the casing, a pair of switch-pieces secured to the transmitter and arranged to move therewith, and an insulating center-piece between the pair of switch-pieces, substantially as set forth.

7. The combination of a case, a transmitter rotatably mounted therein, a switching-device containing stationary contacts in a circle around the axis of the transmitter and a movable contact connected with the transmitter and adapted to move over the stationary contacts and to be operatively set thereto by the rotation of the transmitter.

8. The combination of a case, a transmitter rotatable therein, a circle of switch contacts having the axis of rotation of the transmitter for its center, a rotatable switch-piece adapted to be set by the rotation of the transmitter, and means for limiting such rotation.

9. The combination of a case, a circle of 95 switching contacts therein, a transmitter rotatably mounted in the case, having a hub coincident with the center of said circle of contacts, and provided with a member forming a movable contact-piece to the switching 100 contacts.

10. In a telephone outfit, a switching device containing stationary contact-points in a circle, a rotatable contact-piece arranged axially of said circle for rotation in the case 105 and a transmitter connected with the rotatable contact-piece and constituting the means for setting the contact-piece, and means for indicating the position of the contact-piece.

11. In a telephone-outfit, the combination with a switching device containing a circle of stationary contacts, of a rotatable switch-piece, a rotatable transmitter having its axis of rotation coincident with the switch-piece, means connecting the switch-piece 115 with the transmitter whereby the latter is turned to set the switch-piece.

12. In a telephone outfit, a case, a rotatable transmitter comprising a mouth-piece on the outside of the case and a hub within 120 the case, a contact-piece on the hub a circle of stationary switch-points arranged in operative relation to said contact-piece, and a dial-plate on the hub.

13. In a telephone outfit, the combination 125 of a switching-device having a circle of stationary switch-points, a rotatable transmitter having its axis of rotation coincident with

the center of the circle of switch-points and a contact-piece on the transmitter adapted to close the circuit through any selected one of the switch-points by the rotation of the transmitter, and an indicating device operating to show the position of the contact-piece.

In testimony whereof I have hereunto set

my name to this specification in the presence of two subscribing witnesses.

ALBERT KOCH ANDRIANO.
